United States Patent

Des. 240,653
Patented July 20, 1976

240,653

LIGHTING FIXTURE

Zia Eftekhar, Glendale, Calif., assignor to Lightolier
Incorporated, Jersey City, N.J.

Filed June 20, 1975, Ser. No. 588,802

Term of patent 14 years

Int. Cl. D26—05

U.S. Cl. D48—23 R

FIG. 1

FIG. 2

FIG. 3

FIG. 4

FIG. 1 is a perspective view of the lighting fixture showing my new design;

FIG. 2 is a top plan view thereof on an enlarged scale;

FIG. 3 is a side view thereof on an enlarged scale; and

FIG. 4 is a bottom plan view thereof on an enlarged scale.

I claim:

The ornamental design for a lighting fixture, substantially as shown and described.
